JACKETED EXHAUST PIPE FOR MARINE INTERNAL COMBUSTION ENGINES

Daniel E. Holliday, Sun Valley, Calif., assignor to
Rotary Marine Corporation

Filed Feb. 11, 1974, Ser. No. 441,553

Term of patent 14 years

Int. Cl. D12—16

U.S. Cl. D12—194

FIG. 1 is a perspective view of a jacketed exhaust pipe for marine internal combustion engines embodying my design;

FIG. 2 is a front elevational view thereof;

FIG. 3 is a side elevational view thereof; and

FIG. 4 is a bottom plan view thereof.

I claim:

The ornamental design for a jacketed exhaust pipe for marine internal combustion engines, as shown.
